US0D1095804S

(12) **United States Design Patent** (10) **Patent No.:** **US D1,095,804 S**
(45) **Date of Patent:** **** Sep. 30, 2025**

(54) **CEILING FAN**

(71) Applicant: **Hunter Fan Company**, Memphis, TN (US)

(72) Inventor: **Claire Bernice McRoberts**, La Jolla, CA (US)

(73) Assignee: **Hunter Fan Company**, Memphis, TN (US)

(**) Term: **15 Years**

(21) Appl. No.: **29/835,379**

(22) Filed: **Apr. 19, 2022**

Related U.S. Application Data

(60) Continuation of application No. 29/714,019, filed on Nov. 20, 2019, now Pat. No. Des. 952,127, which is a division of application No. 29/656,393, filed on Jul. 12, 2018, now Pat. No. Des. 872,252.

CLAIM

The ornamental design for a ceiling fan as shown and described.

DESCRIPTION

FIG. 1 is a top perspective view of a ceiling fan, showing my new design;

FIG. 2 is a bottom perspective view thereof;

FIG. 3 is a top view thereof;

FIG. 4 is a bottom view thereof;

FIG. 5 is a rear side view thereof;

FIG. 6 is a left side view thereof;

FIG. 7 is a rear view thereof; and,

FIG. 8 is a front view thereof.

Portions of the ceiling fan shown in broken lines form no part of the claimed design.

1 Claim, 8 Drawing Sheets
